UNITED STATES PATENT OFFICE.

SAMUEL RUSSELL, OF BROOKLYN, ASSIGNOR TO THE AMERICAN ELECTRIC ARMS AND AMMUNITION COMPANY, OF NEW YORK, N. Y.

ELECTRIC GUN.

SPECIFICATION forming part of Letters Patent No. 337,873, dated March 16, 1886.

Application filed May 27, 1885. Serial No. 166,829. (No model.)

To all whom it may concern:

Be it known that I, SAMUEL RUSSELL, a citizen of the United States, residing in Brooklyn, in the county of Kings and State of New York, have invented certain new and useful Improvements in Electric Guns, of which the following is a specification.

This invention relates in general to guns for firing electric cartridges, and in particular to such guns as close the circuit to the cartridge by means of a movable electric firing-pin or electrode moved forward by the pulling of the trigger.

An electric cartridge suitable for firing by this gun is embodied in my Patent No. 307,071, dated October 21, 1884. My improved gun is not, however, confined to the use of the cartridge therein described.

In my Patent No. 307,070, dated October 21, 1884, for "electric gun," I have described an electric gun wherein the circuit is closed by a firing-pin or electrode being pushed forward by the trigger until its front end makes electrical contact with the cartridge as applied particularly to a shotgun the barrels of which "break down" to open the breech.

In an application for patent executed this day, to be filed simultaneously herewith, I have shown and described a bolt-gun and other guns with movable breech-blocks and immovable barrels provided with an improved construction of electric firing devices.

My present invention relates to breech-loading guns having immovable barrels, and in which the breech-block is arranged to move in a vertical plane in order to open the breech and permit the insertion of the cartridge. The well-known Spencer repeating shotgun is a type of gun of this class, and I have selected it to illustrate the embodiment of my invention.

In the accompanying drawings, Figure 1 is an aside elevation, on a reduced scale, of a Spencer repeating shotgun with its breech in section, showing the battery. Fig. 2 is a longitudinal mid-section, on a larger scale, of the breech portion of the gun. Fig. 3 is an elevation, on the same scale as Fig. 2, but looking in the opposite direction, of the breech-block, firing-pin, trigger, and trigger-lock removed. Fig.

4 is an elevation, on a reduced scale, of breech-block, firing-pin, and trigger, showing the breech-block and firing-pin in their three different positions; and Fig. 5 is a fragmentary plan of the junction of the trigger with the 55 firing-pin.

Let A designate the stock of the gun; B, the barrel; C, the breech plate or receiver; E, the vibrating breech-block; F, the firing-pin; H, the firing-pin spring or retracting-spring; 60 T, the trigger, and M the magazine-tube.

N in Fig. 1 is the sliding block by means of which the loading mechanism is worked. O is one of the slides connected thereto, and P is the mainspring for throwing up the 55 breech-block. These parts are all of the usual construction common in the Spencer repeating shotgun, which is so well known as to require no description. Only the firing-pin F and trigger T are altered. The former is 70 bored through or made tubular, and in it is placed an insulated metal contact-pin, I, which I term an "electrode." This pin, which is preferably of hard metal, is insulated from the firing-pin by a tubular sheath, f, of hard 75 rubber or other insulating substance, and projects beyond the firing-pin at both ends, its front end passing through an insulating-bushing, k, in the front of the breech-block, and its rear end sliding through a hole in a metal 80 plate, e, and thereby making electrical contact with said plate.

The electric battery J is placed in the stock of the gun, its opposite poles being connected, respectively, to wires a and b, the former of 85 which leads to any convenient part of the metallic frame of the gun, and thereby connects with either the barrel or breech-block, or both, and the latter leads to the plate e. Thus the electrode I constitutes one terminal of the battery- 90 circuit, while the barrel and breech-block constitute the other terminal thereof.

The metal plate or connection e is arranged in as close proximity as is convenient to the pivot E', for obvious reasons. 95

The usual hammer employed in the Spencer repeater to strike the rear of the firing-pin and drive it against the cartridge is entirely removed from the gun, and the trigger T is connected directly with the firing-pin, so that 100

by pulling the trigger the firing-pin will be pushed forward and the electrode will be brought into contact with the cartridge, thereby closing the circuit through the latter and exploding it. When the trigger is released, the firing-pin and electrode are retracted by the spring H. As the breech-block E, in which the firing-pin is mounted, is pivoted at E', and vibrates about this pivot between the three positions shown in Fig. 4, it is necessary that the trigger shall be connected with the firing-pin in such manner as to admit of this movement and yet nevertheless insure that the pulling of the trigger when the breech-block is in the intermediate or firing position shall effect the pressing forward of the firing-pin and electrode. It is also desirable that the connection shall be such that if the trigger still remains pulled when the breech-block commences its vibratory movement the firing-pin shall free itself from the trigger and be pressed back by its spring before it has moved far enough to injure the projecting front end of the electrode. The connection shown is well adapted to perform these conditions. The trigger is made with a flat spring-arm or elastic plate, t, which extends upward to the firing-pin, being notched at t' to receive the rear end of the latter. The rear portion of the firing-pin is flattened on one side where it comes against the spring-plate t, the front of this flattened portion forming a shoulder, u, against which the front edge of the plate t in the notch t' impinges. Fig. 5 shows the connecting parts of the pin and trigger in the firing position of the breech-block, the plate t of the latter being in section. When the trigger is pulled, the front edge of the plate t bears against the shoulder u and presses the firing-pin forward. If the reloading movement be made while the trigger is still held, the first upward movement of the breech-block carries the pin F out of the notch t', so that the shoulder u is no longer held by the trigger, and the spring H presses the pin back, thus drawing in the projecting front end of the electrode I. The spring-plate t yields laterally to permit of this displacement. The connection of the trigger with the firing-pin is arranged so near to the pivot E' that the movement of the firing-pin due to the vibration of the breech-block is insufficient to disconnect them. The trigger has a slot formed in its lower portion, in which is arranged a locking-bar, l, which turns in fixed bearings in the breech-plates of the gun, and on the outside of the breech is connected to an arm or lever, L, by which it is turned. The bar l is cut away or notched on one side, as clearly shown. When this notched side is uppermost, as shown in Fig. 2, the trigger may be freely pulled, its lower portion moving into this notch; but when the lock is turned as shown in Figs. 1 and 3 the trigger is locked and cannot be pulled, and consequently the electrode cannot be moved forward against the cartridge, and the gun is safe. The lower arm, w, of the trigger is not essential to the lock.

This trigger-lock can be applied to act on any convenient part of the trigger, and it is not confined in its application to this form of trigger. It is to be observed that this lock is applied manually instead of applying itself automatically in loading, like the lock shown in my said patent. 70

As applied to the character of gun herein-before described, my invention has the advantage of dispensing with the hammer, thereby obviating the jar due to the fall of the hammer, and rendering the gun less laborious to operate, since the movement of the slide by the left hand has only to eject the spent shell and transfer a new cartridge to the barrel, being relieved of the necessity of cocking the hammer. 75

My invention is applicable to all breech-loading or magazine guns wherein the breech-block moves in a vertical plane, whether its motion be parallel or vibratory. 80

If other than a vibratory motion be given to the breech-block, the method of making the electrical connection between the battery and the electrode will need to be modified. 85

I claim as my invention—

1. In a breech-loading gun having immovable barrel and a movable breech-block, the combination, with the breech-block mounted to move in a vertical plane to open and close the breech, of an insulated circuit-closing electrode mounted in and borne by said breech-block and moving with the latter and having an independent movement therein toward and from the cartridge, a battery or equivalent source of electric energy, its opposite terminals connected, respectively, to said electrode and to the gun-barrel or breech-block, and the trigger connected to said electrode and adapted, when pulled, to move said electrode forward into contact with the cartridge, substantially as set forth. 95

2. In a breech-loading gun, the combination, with immovable barrel and a pivoted breech-block arranged to vibrate in a vertical plane, of an insulated circuit-closing electrode mounted in and borne by said breech-block and having an independent movement therein toward and from the cartridge, a battery connection with said electrode adjacent to the pivot of the breech-block, a battery with its opposite terminals joined, respectively, to said connection and to the gun-barrel or breech-block, and the trigger connected to said electrode at a point adjacent to the pivot of the breech-block and adapted, when pulled, to move said electrode forward into contact with the cartridge, substantially as set forth. 110

3. In a breech-loading gun, the combination, with immovable barrel and vibrating breech-block, of an insulated circuit-closing electrode mounted in and borne by said breech-block and having an independent movement therein toward and from the cartridge, a battery connected at its opposite terminals to said electrode and to the gun-barrel or breech-block, respectively, and the trigger formed 115

with an elastic arm engaging the said electrode and adapted, when the breech-block is in the position for firing, to press forward the electrode upon being pulled, and to be laterally displaced and disengaged upon the movement of the breech-block, substantially as set forth.

4. The combination, with a pivoted breech-block, E, vibrating in a vertical plane, of a firing-pin, F, mounted therein and adapted to move longitudinally, a shoulder, u, formed thereon, a trigger, T, having elastic plate t notched at t' and adapted to engage said shoulder, an insulated electrode, I, in said firing-pin, and a battery, J, in connection therewith, substantially as set forth.

5. In a breech-loading gun having an immovable barrel and a movable breech-block, the combination, with said breech-block, of an insulated circuit-closing electrode mounted therein and moving therewith and capable of a movement of its own toward and from the cartridge, a retracting-spring mounted in said breech-block and arranged to normally press said electrode back from the cartridge, and a trigger which, when pulled, presses said elec-

trode forward against the tension of said spring, substantially as set forth.

6. In a breech-loading gun having an immovable barrel and a movable breech-block, the combination, with said breech-block, of an insulated electrode mounted therein and moving therewith and having an independent movement therein toward and from the cartridge, an electric battery in connection with said electrode and with the gun barrel or breech-block, a trigger connected to said electrode and adapted, when pulled, to move the same into contact with the cartridge, and a mechanical safety-lock for said trigger, consisting of an oscillating bar arranged close against and in the path of said trigger and having a notch which, when turned toward the trigger, admits the same, substantially as set forth.

In witness whereof I have hereunto signed my name in the presence of two subscribing witnesses.

SAMUEL RUSSELL.
